UNITED STATES PATENT OFFICE.

FRANK SCHNEIDER, OF BUFFALO, NEW YORK.

DESIGN FOR A GOBLET OR SIMILAR ARTICLE.

51,738.

Specification for Design.

Patented Feb. 5, 1918.

Application filed August 20, 1917. Serial No. 187,257. Term of patent 7 years.

To all whom it may concern:

Be it known that I, FRANK SCHNEIDER, a citizen of the United States, residing at Buffalo, in the county of Erie and State of New York, have invented a certain new, original, and ornamental Design for a Goblet or Similar Article, of which the following is a specification, reference being had to the accompanying drawings, forming part thereof, in which—

Figures 1 and 2 are side elevations of a goblet showing my design, said elevations being taken at right angles to each other.

I claim:—

The ornamental design for a goblet or similar article as shown.

FRANK SCHNEIDER.
